TUBE CLEANOUT BRUSH WITH YIELDABLY MOUNTED REMOVABLE WIRE BRISTLES

Matt Simeich, Los Angeles, Calif.

Application May 25, 1948, Serial No. 29,041

3 Claims. (Cl. 15—104.2)

1

My invention relates particularly to brushes adapted for the rapid and efficient removal of incrustations and clogging matter from conduits and tubes, such as drain, waste and sewer pipes and has for its principal objects, to generally improve upon and simplify the construction of existing forms of pipe and tube cleanout brushes, to provide a brush having a plurality of radially disposed tufts or resilient wire bristles and to mount such tufts in the brush body so that they will flex readily in use, with minimum possibility of breakage of the individual bristles at the point where they are connected to said body.

With the foregoing and other objects in view, my invention consists in certain novel features of construction and arrangement of parts which will be hereinafter more fully described and claimed and illustrated in the accompanying drawing, in which:

Fig. 1 is a front end view of my improved brush.

Fig. 2 is an enlarged vertical longitudinal section taken on the line 2—2 of Fig. 1.

Fig. 3 is a cross section on the line 3—3 of Fig. 2.

Fig. 4 is a cross section on the line 4—4 of Fig. 2.

Referring by numerals to the accompanying drawings which illustrate a preferred embodiment of my invention, 10 designates the rear member of the brush body which is tubular in form with its rear end internally threaded for reception of a tubular handle, or the end of a flexible tube 11 of coiled wire and which is generally referred to as a "snake."

The forward end of member 10 is externally threaded and provided with a plurality of short longitudinally disposed slots 12.

Formed at the inner ends of slots 12 is an annular rounded shoulder 13 which serves as a bearing for the looped central portions of the wire bristles of the brush.

The forward member of the brush body comprises a short forwardly tapered body 14 having its rear end internally threaded so as to be screw seated on the threaded forward end of body member 10 and extending forwardly from the rear end of said forward member is an axial bore 15 in which is seated an expansion coil spring 16.

The tufts of bristles 17 used in my improved brush are each formed from a plurality of sections of resilient wire, the central portions of which are looped around a ring 18 and thus, when the tuft

2

carrying ring is inserted in the slotted forward end of member 10, one tuft projects through each slot 12, with the looped inner ends of the tufts bearing on shoulder 13 (see Fig. 2).

To yieldingly maintain the looped portions of the tuft forming wires against shoulders 13, a metal ball 19 is, under the expansive forces of spring 16, pressed against the front sides of the looped portions of the tuft forming wires.

10 In use, the brush by means of its handle, is inserted into and reciprocated within the conduit to be cleaned and as a result of such action, the ends of the tuft will effectively scratch, cut and scrape the inner surface of the conduit to cut, disintegrate and thereby loosen and remove all incrustations from said surface and such action may also be followed in removing clogging bodies of earth, sand or other waste matter.

If desired or necessary, the conduit cleaning 20 functions may be accelerated by delivering water under pressure, through the tubular handle and thereby produce jets which discharge through slots 12.

In addition to cleaning waste, drain and sewer 25 pipes, my improved brush may be advantageously used in cleaning the tubes and flues of boilers and the like.

Thus it will be seen that I have provided a pipe 30 and tube cleanout brush that is simple in structure, inexpensive of manufacture and very effective in performing the functions for which it is intended.

Various minor changes in the size, form and construction of the various parts of my improved 35 cleanout brush may be made and substituted for those herein shown and described, without departing from the spirit of the invention, the scope of which is set forth in the appended claims.

I claim as my invention:

40 1. In a pipe and tube cleanout brush, a hollow body provided in the forward portion of its wall with longitudinal slots, tufts of bristles having their inner ends loosely seated in said body and projecting outwardly through said slots, a ring on 45 which the inner ends of the tufts of bristles are mounted, a nose piece removably mounted on the forward end of said body and yielding pressure means within said nosepiece and bearing on the ends of said bristle tufts within said body.

2. The pipe cleanout brush as set forth in claim

1, and which yielding pressure means comprises a spring pressed ball.

3. A pipe cleanout brush comprising a tubular body provided in its forward end with short longitudinally disposed slots, a ring within the slotted portion of said tubular body, tufts of wire bristles looped about said ring and projecting outwardly through said slots, rounded shoulders at the inner ends of said slots for the inner ends of said tufts of bristles and a spring pressed ball bearing on the inner ends of said tufts of bristles on the opposite sides thereof from said shoulders.

MATT SIMCICH.
